UNITED STATES PATENT OFFICE.

CLINTON R. WEBBER AND GEORGE W. BLOOD, OF SPOKANE, WASHINGTON.

HOOP FOR TANKS.

1,071,120.

Specification of Letters Patent. Patented Aug. 26, 1913.

Application filed February 16, 1912. Serial No. 678,083.

To all whom it may concern:

Be it known that we, CLINTON R. WEBBER and GEORGE W. BLOOD, citizens of the United States, residing at Spokane, in the county of Spokane and State of Washington, have invented certain new and useful Improvements in Hoops for Tanks; and we do hereby declare the following to be a full, clear, and exact description of the invention, such 10 as will enable others skilled in the art to which it appertains to make and use the same.

This invention relates to hoops for tanks and the like and has for an object to provide means for exerting tension upon hoops, the said tension means being disposed within the peripheral surface of the tank.

A further object of the invention is to provide a tank built up of staves having 20 chambers formed in the periphery of such staves at the required points, with hoops embracing the tank having inturned extremities located within the chambers, and tension means also located within the chambers and engaging the inturned ends.

A further object of the invention is to provide improved means for closing and covering the chambers formed in the staves.

With these and other objects in view 30 the invention comprises certain novel constructions, combinations and arrangement of parts as will be hereinafter more fully described and claimed.

In the drawings:—Figure 1 is a view 35 taken transversely to a single stave, showing a chamber formed therein and the inturned extremities of the embracing hoops. Fig. 2 is a perspective view of one of the inturned hoop extremities. Fig. 3 is a view in side 40 elevation of a circular tank or drum provided with the present invention. Fig. 4 is a perspective view of one of the chamber covers.

Like characters of reference indicate corresponding parts throughout the several 45 views.

It is well known that in the ordinary practice of hooping tanks the ends are turned outwardly and tension screws or bolts inserted through such outwardly 50 turned ends. For stationary tanks such construction has few objectionable features but for rotating tanks such as washers or the like, accidents result from such outturned ends catching clothing of operatives, and in 55 other ways. The present invention involves

a means for producing the tension effect upon the hoops embracing the stave structure of the tank without having the ends extend out dangerously beyond the periphery of the tank. For this purpose the hoops 60 10 are provided with inturned ends which are preferably constructed separate and secured thereto, one of the members being shown in perspective at Fig. 2. These in-turned ends 11 are seated in chambers 12 65 formed in the periphery of the stave structure. As shown at Fig. 3, the chambers would be in longitudinal alinement but this of course is wholly immaterial to the construction and some other arrangement of 70 such tension means would possibly increase the strength of the stave structure. Between the inturned extremities 11 a bolt 13 is provided, having a head 14 at one end and a screw threaded portion 15 at the opposite end whereby when the bolt is rotated the extremities 11 are drawn toward each other. When used in conjunction with a rotating tank the chambers 12 receive water or other liquids which by the centrifugal 80 action of the device is thrown outwardly to the annoyance of the operators. To prevent this annoyance, a cover, shown in perspective at Fig. 4, is provided comprising two leaves 16 and 17 hinged together as at 18. 85 The extremities of the leaves 16 and 17 are bifurcated as indicated at Fig. 4 to produce fingers 19 and 20 respectively which are proportioned to pass through notches or openings 21 formed in the extremity members 11. At Fig. 1, one of these cover members is shown in position which closes the outer side of the chamber 12 to prevent water from being thrown from such chamber when the tank is rotated. 95

We claim:—

1. The combination with a tank having a chambered recess formed in its periphery, of a hoop extending about the tank and having inturned rigid extremities disposed within the recess, a tension member disposed within the recess and spanning the interval between the inturned extremities, and a cover member for the recess being substantially flush with the periphery of the tank. 105

2. The combination with a tank having a chambered recess in its periphery, of a hoop extending about the tank and with its extremities located adjacent the walls of the recess, hooked members rigidly secured to 110

the extremities of the hoop and turned inwardly within the recess, a screw bolt located within the recess and spanning the interval between the hooked members, and
5 a cover member engaging the hooked members and closing the recess substantially flush with the periphery of the tank.

In testimony whereof we affix our signatures in presence of two witnesses.

CLINTON R. WEBBER.
GEORGE W. BLOOD.
